UNITED STATES PATENT OFFICE.

HENRY C. BAUMGARDNER, OF ANN ARBOR, MICHIGAN.

SPRAYING DEVICE.

Application filed July 6, 1926. Serial No. 120,785.

The invention relates to spraying devices of that type in which the fluid contents of a receptacle is forced by pressure through a nozzle in the form of a spray. One of the 5 objects of the invention is to provide an improved construction of spraying device which may be manufactured at comparatively low cost and operates in a highly satisfactory manner. Another object is to provide 10 a spraying device with an expandable receptacle which may be readily inserted into another receptacle and which may be readily and quickly drained. With these as well as other objects in view the invention 15 resides in the novel features of construction and combinations and arrangements of parts as more fully hereinafter set forth.

In the drawings:

Figure 1 is a sectional elevation of a 20 spraying device, embodying my invention;

Figure 2 is a plan view thereof;

Figure 3 is an enlarged section through a portion thereof;

Figure 4 is a similar view at right angles 25 to Figure 3.

The spraying device herewith shown has the receptacle 1 which is preferably formed of sheet metal and is cylindrical in shape and the expandable receptacle 2 which is 30 preferably formed of rubber and is located within the receptacle 1. The receptacle 1 has the central fill opening 3 in its upper end which is adapted to be closed by the cap 4 in the nature of a sheet metal disk and 35 located inside the receptacle, there being preferably a gasket 5 formed of suitable material such as rubber permanently secured to the outer face of the cap and engageable with the inner face of the upper end of the receptacle. 6 is a reinforcing ring permanently secured to the outer face of the upper 40 end of the receptacle and having its inner periphery registering with the fill opening 3 and 7 is a bar extending diametrically 45 across the ring and engageable with the outer face thereof, this bar being adapted to be located by means of the pins 8 which extend through the upper end of the receptacle and the reinforcing ring and are adapted to 50 extend through the ends of the bar. 9 is a suitable bolt extending axially through the cap 4 and centrally through the bar 7 and threadedly engaged by the thumb nut 10 which upon tightening clamps the gasket 5 55 firmly against the inner face of the end of the receptacle. 11 is a discharge pipe for

the fluid contents of the receptacle. This pipe extends through the upper end of the receptacle and longitudinally within the receptacle near its side wall and has the series 60 of restricted openings 12 spaced longitudinally thereof with its lower end closed so that possibility of the expandable receptacle entering this discharge pipe and becoming punctured is avoided. The upper end of the discharge pipe is adapted to be connected to the flexible tube 13 having the spraying nozzle 14.

The expandable receptacle is insertable 70 through the fill opening 3 into the receptacle 1 and it is adapted to be connected at one end to the pipe for conducting fluid under pressure and at the other end to the fitting for conducting the fluid from the expandable receptacle. As shown, the upper end of the 75 expandable receptacle has connected thereto the fitting 15 which has the threaded hollow stem 16 and the inner and outer clamping members 17 and 18, respectively, the inner clamping member being located within the 80 expandable receptacle and the outer clamping member being threaded upon the stem and engageable with the outer side of the expandable receptacle, a suitable gasket 19 85 preferably formed of rubber being located between the inner side of the expandable receptacle and the clamping member 17. 20 is a pipe for conducting fluid under pressure to the expandable receptacle 2. This pipe 90 extends through the side wall of the receptacle 1 near its lower end and longitudinally within this receptacle near its side wall and through the upper end thereof. 21 is a suitable spring pressed valve within the lower end portion of the pipe 20 and adapted to 95 permit the passage of fluid under pressure into this pipe but prevent passage of the fluid in the reverse direction. 22 is a pressure gage above the upper end of the receptacle 1 and connected to the pipe 20 and 100 23 is a transverse branch of the pipe 20 which is adapted to be connected to the fitting 15 by means of the coupling 24 upon the branch 23 and adapted to thread upon the stem 16 of the fitting.

To provide for the discharge of the fluid from the expandable receptacle and thereby permit this receptacle to contract, I have provided the fitting 25 which has a passage-way extending through the receptacle 1 and 110 communicating with the interior of the expandable receptacle 2. This fitting is con-

structed to provide the maximum size of discharge passageway with the minimum size of fitting and furthermore is so constructed that the expansible receptacle may be readily removed or reinserted into the main receptacle. In detail, the fitting has the pair of sections 26 and 27 which are respectively located upon the inner and outer sides of the expansible receptacle 2 and are adapted to be clamped against the wall of this receptacle by means of the screws 28. Suitable gaskets 29 preferably formed of rubber are located adjacent the inner and outer sides of the expansible receptacle to seal the joint between this receptacle and the sections 26 and 27. These sections have the axial openings 30 and 31, respectively. 32 is a third section of the fitting which is located at the outer side of the bottom of the receptacle 1 and is adapted to be clamped thereagainst by suitable means such as the nuts 33 which are threaded upon the studs 34 extending through the section 27 and fixedly threaded in the section 26. 35 is a gasket preferably formed of rubber located at the inner side of the bottom of the receptacle for sealing the joint between the section 27 and the bottom when the nuts 33 are tightened up. The section 32 has the transverse recesses 36 in its upper face and adapted to communicate through the opening in the bottom of the receptacle with the axial openings 30 and 31. For controlling the discharge of the fluid from the expansible receptacle 2 through the discharge passageway formed by the openings 30 and 31 and the recesses 36, I have provided the valve 37 which is preferably formed of rubber and is located within the expansible receptacle and engageable with the upper end of the opening 30. 38 is a valve stem extending axially through the openings 30 and 31 and also the section 32 and 39 is a thumb nut threadedly engaging the same below the section 32 for adjusting the valve 37 which is fixedly held upon the valve stem 38 so that this valve may be moved to either open or closed positions. With this construction it will be seen that the fitting may be made comparatively small and at the same time the discharge passageway for the fluid from the expansible receptacle may be made relatively large so that this expansible receptacle may be quickly drained. It will further be seen that by removing the thumb nut 39 and the nuts 33 the sections of the fitting located within the receptacle 1 may be unloosened from its bottom.

40 is a strap which is connected at its ends to the side wall of the receptacle 1, this strap being preferably flexible to conform to the shoulder of a person while carrying the spraying device around.

From the above description it will be readily seen that the expansible receptacle

2 may be readily inserted into the receptacle 1 through the fill opening 3 and its upper end connected to the pipe 20 and its lower end secured to the bottom of the receptacle 1 and the discharge valve moved to closed position. The solution or liquid to be sprayed may also be inserted into the tank 1 through the fill opening, after which the cap 4 may be firmly secured in place. The receptacle 1 is then air tight. The pipe 20 then may be connected to a water faucet and water admitted to exert a predetermined pressure, which will be indicated by the gage 22. The expansible receptacle in expanding exerts pressure upon the solution to be sprayed and forces the same out of the receptacle 1 through the discharge pipe 11, tube 13, and spraying nozzle 14. After the spraying device has been used the expansible receptacle 2 may be quickly drained and readily removed from the receptacle 1 and cleaned. To remove the receptacle 2 from the container the wing nut 10 is loosened allowing the plate 4 to clear the receptacle 1. When the plate is in this position the operator merely slips a wire or other suitable means around the plate to prevent the same from falling to the bottom of the receptacle when the wing nut is removed from the bolt 9 which is anchored upon the plate 4. Thus the plate 4 may be swung to one side of the opening 3 permitting a removal of the expansible receptacle.

What I claim as my invention is:

1. In a spraying device, the combination with a normally closed receptacle for containing a spraying fluid and a discharge pipe in a communication with the interior thereof, of an expansible receptacle within said first-mentioned receptacle, a pipe for conducting fluid under pressure extending through said first-mentioned receptacle and communicating with the interior of said expansible receptacle, a fitting having a passageway extending through said first-mentioned receptacle and communicating with the interior of said expansible receptacle, a valve within said expansible receptacle for closing said passageway, and means operable from outside said first-mentioned receptacle for actuating said valve.

2. In a spraying device, the combination with a receptacle for containing a spraying fluid having a fill opening, means for closing said fill opening and a discharge pipe in communication with the interior of said receptacle, of a second pipe extending through said receptacle, an expansible receptacle insertable through said fill opening into said first-mentioned receptacle and detachably connected to said second pipe, a sectional fitting detachably secured to said first-mentioned receptacle and having a passageway extending therethrough and communicating with the interior of said expansible

receptacle, and a valve associated with the fitting for closing the passageway.

3. In a spraying device, the combination with a normally closed receptacle and a discharge pipe in communication with the interior thereof, of an expandible receptacle within said first-mentioned receptacle, means extending through said first-mentioned receptacle for conducting fluid under pressure 10 to said expandible receptacle and a sectional fitting comprising sections within said first-mentioned receptacle and clamped against opposite sides of said expandible receptacle and having aligned openings therethrough 15 for the discharge of the fluid from said expandible receptacle, another section outside said first-mentioned receptacle having an opening for communicating with the openings of said first-mentioned sections, means for clamping 20 one of said first-mentioned sections and said last-mentioned section against opposite sides of said first-mentioned receptacle, and a valve operable from outside said first-mentioned receptacle for controlling the discharge of the fluid through said fitting. 25

4. In a spraying device, the combination with a receptacle for containing a spraying fluid and a discharge pipe in communication with the interior thereof, of an expandible receptacle within said first-mentioned receptacle, means extending through said first-mentioned receptacle for conducting fluid under pressure to said expandible receptacle and a fitting for conducting fluid from said 30 expandible receptacle through said first-mentioned receptacle, said fitting comprising a pair of sections clamped against opposite sides of said expandible receptacle and having axial openings therethrough for the passage of the fluid from said expandible receptacle, another section having a transverse recess for communicating with the openings in said first-mentioned sections, means for clamping one of said first-mentioned sections and said last-mentioned section against 35 opposite sides of said first-mentioned receptacle, a valve within said expandible receptacle for closing the opening through the sections at the inner side of said expandible receptacle, a valve stem extending axially through said sections, and means operable from outside said first-mentioned receptacle for actuating said valve stem. 40

5. In a spraying device, the combination 45 with a normally closed receptacle and a discharge pipe in communication with the interior thereof, of an expandible receptacle within said first-mentioned receptacle, a pipe extending through said first-mentioned receptacle and communicating with the interior of said expandible receptacle, and a sectional fitting comprising sections within said first-mentioned receptacle and clamped against opposite sides of said expandible 50 receptacle and having aligned openings there-

through for the discharge of the fluid from said expandible receptacle, and a valve associated with said fitting for controlling the discharge of the fluid.

6. In a spraying device, the combination 70 with a normally closed receptacle for containing a spraying fluid and means for discharging said fluid, of an expandible receptacle within said first-mentioned receptacle, a fitting having a passageway therein for discharging the fluid in said expandible receptacle, and means within said last-mentioned receptacle for controlling the discharge of the fluid through said fitting. 75

7. In a spraying device, the combination 80 with a receptacle for containing a spraying fluid having a fill opening, of a closed expandible receptacle insertable through said opening into said first-mentioned receptacle, and detachable means for conducting fluid 85 under pressure to said expandible receptacle including a fitting comprising sections within said first-mentioned receptacle and clamped against opposite sides of said expandible receptacle, one of said sections having a passageway therethrough permitting the fluid to enter the expandible receptacle, and a valve for preventing passage of the fluid in a reverse direction. 90

8. In a spraying device, the combination 95 with a normally closed receptacle for containing a spraying fluid, of an expandible receptacle within said first mentioned receptacle, a discharge pipe extending into said first mentioned receptacle, and means for 100 supporting said expandible receptacle in said first mentioned receptacle including sectional fittings secured to the top and bottom of said expandible receptacle, one of said fittings operable to conduct fluid under pressure into the expandible receptacle for expanding the same and forcing the spraying fluid contained in the first mentioned receptacle out through said discharge pipe. 105

9. In a spraying device, the combination 110 with a normally closed receptacle for containing spraying fluid, of an expandible receptacle within said first mentioned receptacle, a discharge pipe extending into said first mentioned receptacle, and means for 115 supporting said expandible receptacle in said first mentioned receptacle including sectional valve controlled fittings secured respectively to the upper and lower portions of said expandible receptacle, one of said fittings operable to conduct fluid under pressure into the expandible receptacle for expanding the same to force the spraying fluid contained in the first mentioned receptacle through said discharge pipe and the other of said 120 fittings operable to discharge the fluid contained in the expandible receptacle to permit the same to contract. 125

10. In a spraying device, the combination 130 with a normally closed receptacle for con-

taining a spraying fluid, and a discharge pipe extending into said receptacle and provided with a plurality of restricted openings, of an expansible receptacle within said first mentioned receptacle, and a valve controlled passage extending through said first mentioned receptacle and provided with a sec-

tional fitting having portions clamped upon opposite sides of said expansible receptacle for conducting fluid under pressure into the latter.

In testimony whereof I affix my signature.

HENRY C. BAUMGARDNER.
